(57) **CLAIM**

The ornamental design for a television receiver, as shown and described.

DESCRIPTION

FIG. 1 is a front perspective view of a television receiver, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The short dash-dash lines that are immediately adjacent the shaded areas and define unshaded regions represent the bounds of the claim and are not included in the claim. All other short dash-dash broken lines are directed to environment and are for illustrative purposes only. All of the broken lines throughout the views form no part of the claimed design.
